UNITED STATES PATENT OFFICE

2,441,138

APPARATUS FOR DRYING HAIR WITH LIQUEFIED GAS

Esther R. Elder, Pasadena, Calif., assignor of forty per cent to William R. Harriman, Hondo, ten per cent to Esther Anne Harrington, Pasadena, and ten per cent to Mary Ellen Peachman, San Francisco, Calif.

Application December 20, 1944, Serial No. 569,026

1 Claim. (Cl. 34—99)

1

My invention relates to an apparatus for drying the hair. Since excess of heat is deleterious to human hair, it is an object of the present invention to provide a method and apparatus for drying hair with a minimum of heat, the degree of heat to be applied being variable and under the personal control of each individual.

Another object of the invention is to provide such apparatus which will decrease the time required to dry the hair without correspondingly increasing the temperature to which the hair is subjected.

A further object of the invention is to provide such apparatus for quickly and comfortably supplying the hair to be dried with gas, such as CO₂, or a mixture of gases, such as air, having a minimum of moisture content, said gases being supplied in liquid form, and then vaporized and heated.

My invention also has for its objects to provide such apparatuses that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a schematic elevational view, partly in section, of an embodiment of my invention.

Fig. 2 is a sectional view on the line 2—2 of Fig. 1, showing the construction of the drying chamber.

Fig. 3 is a sectional view on the line 3—3 of Fig. 1, showing one form of fluid heating means, and a variable control therefor.

The method and apparatus of this application is related to a method and apparatus for drying industrial products, disclosed and claimed in an application filed by me on the same date, and given Serial Number 569,025.

The apparatus for carrying out the method of my invention consists generally of a supply tank 10 of liquid gas or dry ice, a gas heating and mixing means 20, and the hair drying chamber 40. The supply tank 10 is provided with the usual pressure gauges (not shown), and is readily connected or disconnected.

2

The liquified gas in supply tank 10 is released in vapor form by control valve 12 to conduit 14, thence through a timing or measuring device 16, and into a heating and mixing chamber 21 which is substantially a vaporizing or expansion chamber. Since the vaporized gas would be too cold for comfort, a heating means of any suitable type, such as the electric resistance heating coil 23, is provided in chamber 21. A variable resistance 25, or other suitable control, permits the individual whose hair is being dried, to personally control the temperature of the drying gas. The deflecting vanes 27 of any suitable design, and fan 29 agitate the drying gas to make sure it will be delivered to the drying chamber 40 at a uniform temperature throughout.

The uniformly heated drying gas is conducted from the chamber 21, through flexible conduit 30 into drying chamber 40. To prevent the drying gas from being wasted, and to insure its uniform contact with the head of hair to be dried, the drying chamber 40 is made in the form of a loosely fitting cap portion 41, and a snugly fitting brim or mouth portion 43, which may be made from sponge rubber or other suitable material which is adjustable to different size heads, is comfortable to wear, and which will satisfactorily confine the drying gas in the cap portion 41. The brim or mouth portion 43 is provided with an annular port 45, or other suitable means such as spaced jets (not shown) for supplying the drying gas fairly uniformly to all of the hair. The drying gas is admitted to the annular port 45 through the inlet 47, while the moisture-laden gas is discharged to the atmosphere through outlet 48.

Method of operation

40 The method of drying hair invented by me, is quick, comfortable, and will not injure the hair. By reducing the time required for drying the hair, the capacity of the equipment in a beauty parlor is increased, and the customer's time is saved.

45 The liquified gas, such as CO₂, or mixture of gases, such as air, is substantially moisture free, and is readily supplied to beauty parlors in interchangeable tanks 10.

Upon being released from tank 10, by means of a control valve 12, the liquified gas is vaporized, and as a result becomes too cold to use for drying a person's hair. A measured or timed amount of the cold dry gas is metered through the device 16 into the heating and mixing chamber 21, where the deflecting vanes 27 direct the unheated gas to all parts of the heating means

23, while the fan 29 mixes the heated gas to a uniform temperature throughout. This temperature is under the direct control of the individual whose hair is being dried, since it may be varied by means of the variable resistance 25, or by other suitable means, where the heating means 23 is not in the form of an electric resistance heating coil.

The dry, uniformly heated gas enters the inlet 47 of the drying chamber 40, which has been fitted snugly to the wearer's head. Said drying gas is distributed by any suitable means, such as the annular port 45, into direct and intimate contact with the wet hair and scalp. Since the drying gas is almost entirely free of moisture, it dries the hair and scalp more quickly and efficiently than ordinary heated air or radiant heat. Since a lower temperature can be used because of the greater efficiency, the use of the drying chamber of my invention is more comfortable than the ordinary hood. The moisture-laden gas is discharged to the atmosphere through outlet 48. The efficiency is, therefore, not affected by variations in humidity of the ambient air, as are methods and apparatus utilizing ordinary moisture containing air.

While I have illustrated and described what I now regard as the preferred embodiments of my invention, the steps and sequences of steps are, of course, subject to modifications without departing from the spirit and scope of my invention. I, therefore, do not wish to restrict myself to the particular steps or sequences of steps described hereinbefore, but desire to avail myself of all modifications that may fall within the scope 35 of the appended claim.

Having thus described my invention, what I claim and desire to secure by Letters Patent is:

5 Hair drying apparatus, comprising a source of liquified gas, a chamber for vaporizing said gas, means for measuring the flow of said gas to said chamber, a heating means within said chamber, manual means to control said heating means, a deflector in said chamber disposed in the path of the gas released from said source to deflect the gas stream onto and through said heating means, means to move the gas through said deflecting means and heating means and to mix the gas to a uniform temperature, a conduit for conducting the gas so treated to the hair, and means to discharge the gas to the atmosphere, after passing over a user's head.
